PAPER-BACK FABRICS FOR REINFORCING WORK

Charles F. Bailey and Julius P. Distler, Peoria, Ill., assignors to Keystone Steel & Wire Company, Peoria, Ill., a corporation of Illinois

Application April 23, 1934, Serial No. 721,928

5 Claims. (Cl. 72—119)

This invention has reference to paper-back fabrics such as are used in construction work as a reinforcement and support for plastic materials, as plaster, stucco, cement, concrete and the like.

5 The invention has for its principal object to improve the method of reenforcing the paper-backing on the wire netting and the securing means for uniting the netting to the paper-backing and reenforcement into a unitary structure, 10 whereby the unit is stiffened and canting or slipping of one of the elements on the other is prevented and the handling of the structure thereby facilitated with ease and dispatch.

A further object is to strengthen and stiffen the 15 paper-back fabric with elements which, when the fabric is in position against vertical spaced studding, will extend cross-wise of such studding and thereby afford a much better support for the fabric when the plastic material is applied.

20 A still further object is to staple the netting to the paper-backing and to the reenforcing elements, preferably where the warp and woof wires of the netting are joined and to reverse the arrangement of adjacent staples throughout the 25 width of the netting and by so doing hold the netting on the paper-backing so as to prevent canting or slipping of one element on the other.

That the invention may be more fully understood reference is had to the accompanying drawing, in which:—

Fig. 1 is a diagrammatic face view showing the manner in which our paper-back fabric is applied to studding;

Fig. 2 is a diagrammatic edge view of Fig. 1; 35 Fig. 3 is a detail view of our improved paper-back fabric;

Fig. 4 is a detail, in section, as the same would appear if taken on the line 4—4 Fig. 3, and

40 Fig. 5 is a detail, in section, as the same would appear if taken on the line 5—5 Fig. 3.

Like characters of reference denote corresponding parts throughout the figures.

The composite structure comprising our invention includes a wire netting 1, a paper-backing 2, the reenforcing members 3 and staples 4, for securing netting, backing and reenforcing members together.

50 The netting is exhibited as a straight line netting although it may be of hexagonal or other type, if desired. In the present form the netting is made up of warp wires 5 and woof wires 6 which are twisted together at points of intersection, as at 7.

55 The backing 2 is a preferably tough paper sheet,

although it may be of any material suitable for the purposes intended.

The reenforcing members 3 are preferably wires, but may be any material and of any design. They are, however, disposed next adjacent the outside rear face of the backing and disposed transversely to the warp wires 5 terminating at opposite edges of the backing. We also prefer that the marginal wires of the netting shall lie outside of the opposite edges of the backing, as shown in Fig. 3. 10 Furthermore, these members 3 preferably coincide with and cross the twisted portions 7 of the warp and woof wires, which are disposed next adjacent to and on the other side of the backing.

For securing the netting, backing and reenforcing members into a unitary structure we preferably employ wire staples 4, the arcuate portions 8 of which lie diagonally across the twisted portions 7 of the warp and woof wires, with ends of the staples pierced through the backing 2 and 20 their ends bent over or about the reenforcing members 3, somewhat in the manner seen in Figs. 4 and 5. In the application of the successive staples cross-wise of the netting, see Fig. 3, which is lengthwise of the members 3 we prefer that the 25 arcuate ends of adjacent staples shall be opposite, one to the other, as shown. In this way we materially stiffen the connection between the netting and backing and prevent any canting or slippage of either of the elements 1 or 2 on the 30 other. Since these paper-back fabrics are sometimes furnished in sheets this materially aids in the handling of the same, but whether furnished in sheets or in rolls the rigidity of the structure is the same. Furthermore, by disposing the elements 3 cross-wise of the netting and with the manner of securing the same to the netting and backing by the staples, the user is assured of a 35 materially stiffened article when applied to studding as in Fig. 1, as the members 3 will extend 40 cross-wise of the studding to which the paper-back fabric is applied giving it a better support and provide a substantial means for direct connection to the studding, as will be understood.

What we claim is:—

1. In a paper-back fabric for reenforcing work, the combination of a wire netting, a paper-backing, spacing members disposed in spaced relation against the back of the paper, and wire clips engaging strands of the netting with the ends of 50 the clips piercing the paper upon opposite sides of the strands thereof and upon opposite sides of said members, said clips having each of their ends bent around the members to form dual separate hooks embracing the members for uniting 55

the netting, paper-backing and members into a composite structure.

2. In a paper-back fabric for reenforcing work, the combination of a wire netting composed of a plurality of straight line warp wires and a woof wire woven across the line wires and twisted therewith at their intersections, a paper-backing, spacing members disposed in spaced relation against the back of the paper and arranged to extend cross-wise of the warp wires in coincidence with twists of the warp and woof wires, and wire clips engaging certain of the twists and having their ends piercing the paper-backing upon opposite sides of the twists, said clips having each of their ends bent over the members in such a manner as to form dual separate hooks embracing said members for uniting the netting, paper-backing and members into a composite structure.

3. In a paper-back fabric for reenforcing work, the combination of a wire netting composed of a plurality of straight line warp wires and a woof wire woven across the line wire and twisted therewith at their intersections, a paper-backing, spacing members disposed in spaced relation against the back of the paper and arranged to extend cross-wise of the warp wires in coincidence with twists of the warp and woof wires, and wire clips engaging certain of the twists and having their ends piercing the paper-backing and bent over from opposite sides of the members in such a manner as to form dual separate hooks embracing the members for uniting the netting, paper-backing and members into a composite structure, the adjacent clips cross-wise of the fabric disposed reversely to each other to additionally stiffen and strengthen the fabric.

4. In an article of the character described, the combination of a wire netting the wires constituting which are twisted together, a sheet of material lying next adjacent thereto and providing a backing therefor, reenforcing members disposed next adjacent the outside face of such material and extending cross-wise thereof from one edge to the other and cross-wise of the twist-connected portions of said wires, and staples connecting said netting, material and reenforcing members, the arcuate portions of the staples disposed diagonally across the twist-connected portions of the wires with the ends of the staples piercing the material and bent about said reenforcing members to form dual separate hooks embracing the members. 15

5. In an article of the character described, the combination of a wire netting the wires constituting which are twisted together, a sheet of material lying next adjacent thereto and providing a backing therefor, reenforcing members disposed next adjacent the outside face of such material and extending cross-wise thereof from one edge to the other and cross-wise of the twist-connected portions of said wires, and staples connecting said netting, material and reenforcing members, the arcuate portions of the staples disposed diagonally across the twist-connected portions of the wires with the ends of the staples piercing the material and bent about said reenforcing members to form dual separate hooks embracing the members, the arcuate portion of adjacent staples throughout the length of each reenforcing member being disposed in opposite positions, whereby to give added stiffening to the composite structure. 20 25 30
